APPARATUS FOR ABRASIVELY TREATING
METALLIC OBJECTSDavid C. Turnbull, Mishawaka, Ind., assignor to
The American Foundry Equipment Company,
Mishawaka, Ind., a corporation of DelawareApplication June 17, 1936, Serial No. 85,645
Renewed November 19, 1938

18 Claims.

(Cl. 51—9)

This invention relates to apparatus for abrasively treating metallic objects.

In cleaning, polishing, hardening or treating metallic castings and forgings or otherwise modifying the surface characteristics thereof, it is generally desirable to expose all or predetermined portions of the surfaces of the articles uniformly to the action of the stream of abrasive or treating material. Where the articles to be treated are relatively small and rugged they can be exposed conveniently for treatment in a tumbling mill. However, tumbling is not suitable in many instances as, for example, where the articles are large and heavy, or are delicate and brittle, or have substantial projections, or where they have relatively deep cavities or openings. Furthermore, it is often desirable to expose the articles to be treated to the abrasive stream in a predetermined manner in order to insure complete treatment of certain portions or all of the surface of each article, which cannot be properly effected in tumbling mills as heretofore constructed.

Where relatively large quantities of articles are to be treated, it is also desirable to pass them in succession through the abrasive stream in a more or less continuous feeding operation to eliminate the necessity for shutting down the apparatus, as is necessary in batch operations. Preferably, the operation should be adapted to be carried out partially or completely by automatic apparatus.

According to the present invention, the article to be treated is supported on a suitable conveyor mechanism which imparts to the article a generally screw-like movement, comprising a rotational or turning movement and a forward or linear movement through the stream of treating particles projected by suitable abrasive-throwing apparatus. The treating stream is projected in a fan-like formation whereby the several portions of the stream strike the article at varying angles along its path of movement, thereby effectively and uniformly treating the various surfaces, cavities and projections thereof.

The present invention also provides suitable apparatus for carrying out the novel process, which apparatus includes one or more abrasive-projecting devices which preferably are of the centrifugal throwing wheel type provided with means for controlling the direction of flight of the thrown abrasive. A conveyor mechanism for advancing the articles through the stream is provided and includes a plurality of cradle members mounted for rotation about a common

axis and associated with control means for bringing the cradle members successively into article-supporting position and thereafter imparting a turning movement to the article while thus supported. The cradle members are also actuated to advance the articles forwardly through the abrasive stream simultaneously with the turning movement. A loading mechanism is provided for depositing the articles to be treated gently on the conveyor in predetermined position. Unloading or discharge mechanism is provided for receiving the treated articles from the conveyor and removing them therefrom.

One or more abrasive-throwing wheels are provided, comprising a plurality of spaced radially arranged blades extending substantially from the periphery of the wheel inwardly short of the axis of rotation to define a central opening. An impeller rotatable with the throwing blades is positioned within the central opening and a normally stationary control member having a discharge outlet therein surrounds the impeller. The discharge outlet in the control member may comprise a series of openings dimensioned to provide substantially even distribution of the abrasive over the work surface.

The present invention provides apparatus by which castings, forgings, or other articles can be quickly and effectively cleaned, polished, hardened or otherwise treated with a maximum of efficiency and with the assurance that predetermined surface portions or all of the surfaces, including the surfaces of projections and cavities, are fully and uniformly treated. The apparatus is suitable for continuous and semi-automatic or fully automatic operation.

Various other features and advantages of the invention will be apparent from the following particular description and from an inspection of the accompanying drawings.

Although the novel features which are believed to be characteristic of this invention will be particularly pointed out in the claims appended hereto, the invention itself, as to its objects and advantages, and the manner in which it may be carried out, may be better understood by referring to the following description taken in connection with the accompanying drawings forming a part thereof, in which:

Fig. 1 is a side elevational view showing one form of apparatus suitable for carrying out the present invention;

Fig. 2 is a rear end elevational view of the apparatus shown in Fig. 1;

Fig. 3 is an enlarged fragmentary side eleva-

tional view of a portion of the apparatus shown in Fig. 1, certain parts of the structure being broken away to expose the interior;

Fig. 4 is an enlarged fragmentary view partly in cross-section, of the driving head at the charging end of the apparatus (right-hand end, as viewed in Fig. 1) and adjacent portions of the structure;

Fig. 16 is a perspective view of one of the throwing blades of the wheel shown in Fig. 13;

Fig. 17 is a perspective view of the control member of the wheel shown in Fig. 13; and

Fig. 18 is a diagrammatic view of the wheel of Fig. 13 in position over a work piece and illustrating the direction of flight of the abrasive thrown from the wheel.

In the following description and in the claims, various details will be identified by specific names for convenience, but they are intended to be as generic in their application as the art will permit. Like reference characters denote like parts in the several figures of the drawings.

In the drawings accompanying and forming part of this specification, certain specific disclosure of the invention is made for purposes of explanation, but it will be understood that the details may be modified in various respects without departure from the broad aspect of the invention.

The invention may be carried out with any one of a number of types of abrasive projecting devices but I prefer to use an abrasive projector of the centrifugal throwing wheel type provided with means for controlling the flight of the abrasive. One novel form of projector suitable for carrying out the invention is disclosed herein.

For purposes of illustration the wheel is shown in Figs. 13 and 14 as comprising spaced parallel side plates 2 and 3 suitably secured to-

gether by studs 4 having reduced end portions 5 entering openings 6 in the side plates and secured as by plug welding. The side plate 2 preferably is secured as by bolts 7 to a hub member 8 which is suitably mounted on a shaft 9.

Throwing blades 10 are disposed between and carried by the side plates 2 and 3 and extend substantially radially thereof from the periphery to points inwardly short of the center. Each throwing blade 10 may be formed with side flanges 11 adapted to seat in grooves 12 in the side plates 2 and 3 and is secured by a screw 13 extending through the side plate 3 and entering a recess 14 which may be formed in the blade 10.

Disposed in the generally circular space defined by the ends of the throwing blades 10 is an impeller 15, which may include spaced parallel side plates 16 and 17 and a plurality of radially extending blades 18. The impeller 15 is suitably secured, as by a bolt 19, to a center plate 20 which preferably is supported in the side plate 2, as by screws 21.

Surrounding the impeller 15 and disposed within the space between the ends of the blades 10 is a control member 25 preferably of generally cylindrical form. The control member 25 has a trough-like extension 26 projecting through an opening 22 in the side plate 3 and is partially closed at the other end by an inwardly turned flange 27. Preferably, the control member 25 is suitably mounted in fixed position as by a member 28 disposed outside of the wheel and is adjustable about its axis for a purpose which will hereinafter appear. The control member 25 is provided with a discharge aperture, desirably in the form of a series of spaced openings, such as openings O¹, O², O³ and O⁴, extending longitudinally of the control member a distance approximately equal to the length of the impeller blades 18, and aligned therewith.

A circular gasket 29 may be provided to prevent abrasive from working in between the side plate 3 and the blades and may be of suitable wear-resisting material, and a projecting ring 30 may be provided for protecting the front face of the wheel. A suitable feeding means, such as a feed pipe 31, is provided for supplying abrasive to the impeller 15 through opening 23 therein.

The wheel is operated by rotating the shaft 9 which effects rotation of the impeller 15 and the side plates 2 and 3 carrying the throwing blades 10. Abrasive is fed to the impeller 15 through the feed pipe 31 and the impeller 15 hurls the abrasive through the discharge openings O¹, O², O³ and O⁴, and the abrasive is deposited on the throwing blades 10 as they pass the several openings. The abrasive is carried along the leading surface of each throwing blade 10 by centrifugal force and is projected from the throwing blades 10 adjacent the periphery by combined centrifugal and rotary force, along a path a until it impinges against the surface of the work piece w. The abrasive is thrown from the blades 10 and spreads out fanwise to form a stream which is approximately equal to the width of the throwing blades so that the composite portions of the stream impinge against the work piece w at different angles. Thus, when a substantially flat work piece is positioned adjacent the wheel in a manner similar to that shown in Fig. 18, a substantially elongated rectangular impingement

pattern of substantially uniform density is produced.

Although a single discharge opening may be provided in the control member 25, preferably a plurality of openings such as the openings O¹, O², O³ and O⁴ are provided, and the openings may be of successively increasing length in the direction of rotation of the wheel. Thus, the abrasive is projected from the wheel in a series of adjacent streams a¹, a², a³ and a⁴ corresponding to the openings O¹, O², O³ and O⁴, respectively.

A fixed relationship exists between the clock-dial position of the discharge openings O¹, O², O³ and O⁴ of the control member 25 and the point of discharge of the abrasive from the throwing blades 10. By adjusting the position of the discharge openings O¹, O², O³ and O⁴, the direction of the abrasive thrown by the wheel may be regulated and controlled. The provision of a plurality of openings which increase progressively in area in the direction of rotation of the wheel results in a substantially uniform density of abrasive in any transverse cross-section of the abrasive stream and thus the substantially uniform impingement of the work piece is produced.

Referring now to Fig. 1, the apparatus comprises a base support 49 mounting a housing 50 which is divided by partition members 51 and 52 into a loading chamber 53, a treating chamber 54 and an unloading chamber 55. A conveyor 56 extends substantially throughout the housing and suitably shaped openings 57 and 58 are provided in partitions 51 and 52 for accommodating the conveyor 56.

Mounted on the top wall of the housing 50 is a plurality of abrasive projectors B and C which, by way of example, may be of the type hereinbefore described. The projector B is mounted adjacent an opening 60 in the top wall of the housing and may extend partially therethrough so as to project an abrasive stream b into the treating chamber 54. The projector B is mounted on a shaft 61 (Figs. 2 and 9) journaled in bearings 62 and carrying a pulley 63. A belt 66 is trained over the pulley 63 and also over a pulley 65 connected to the drive shaft of a motor 64 for driving the projector B. The projector B may be enclosed in a suitable housing 68 which may be hinged at 69 to the housing 50 and latched in position by a latch 70.

A second projector C (Fig. 3) may be provided for throwing an abrasive stream c and may be constructed similar to the projector B and driven in a similar manner. However, preferably the projector C is mounted to rotate in a reverse direction with respect to the projector B so that the abrasive stream c is directed oppositely to the abrasive stream b.

The projectors B and C (Fig. 1) are supplied with an abrasive material, such as shot, steel grit, or the like, from a hopper 75 from which extends a conduit 76 feeding a hopper 77. Branch conduits 78 extending from the hopper 77 lead to the projectors B and C respectively. Each conduit 78 supplies a feed-pipe 79 supported on a bracket 80, which conducts the abrasive into the wheel. A control valve 81 is provided in each conduit 78 for controlling the supply of abrasive material.

Disposed below the housing 50 (Figs. 1 and 2) is a hopper 85 which may be disposed in a suitable pit 86. The hopper 85 is adapted to collect abrasive which has been projected into the chamber 54. The abrasive is withdrawn from the hopper 85 by a screw conveyor 87 communicating

with a second conveyor 88 which conveys the abrasive to an elevator 89. A motor 90 is connected by a chain drive 91 to the conveyor 88 and the latter is connected by a chain drive 92 to the conveyor 87. A motor 93 may be provided for driving the elevator to elevate the abrasive from the pit 86 to the cleaner 75 from whence it flows by gravity through the conduit 76 to the hopper 77 and is again thrown by the projectors.

Referring to Fig. 8, the housing 50 is provided with a loading opening 100 for permitting access to the loading chamber 53. Mounted in position to enter the opening 100 is a loading frame 101 comprising a plurality of frame members 102 having at their lower ends sector plates 103 formed with arcuate edges 120 adapted to rock on a shelf 121 and with upright edges 104 adapted, when in one position, to lie against a vertical wall of the housing 50. Extending between the sector plates 103 is a shaft 105 carrying rollers 106 adapted to ride along the curved edges 107 of a plurality of spaced guide plates 108 mounted on a bracket 109 within the housing 50.

The frame members 102 carry at their upper ends plates 110 connected by shafts 111 and 112, which extend beyond the plates 110 and carry side plates 113. The shaft 114 is supported by the outer plates 113 and serves as a handle for the loading frame 101. A rack 115 is carried by the upper ends of the frame members 102 and comprises a plurality of spaced bars 116 having adjacent inner end lugs 117. Webs 118 extend from the frame members 102 and support the bars 116. The lower shaft 112 extends beyond the outer plates 113 and is adapted to strike against stop brackets 119 secured within the housing.

For the purposes of illustration, the work pieces or articles treated are represented by cylinder blocks M; however, it will be understood that the invention is not limited to the treatment of such articles but is adapted to treat any one of a large number of articles of various shapes and sizes; furthermore, articles of various shapes and sizes can be treated successively in the same apparatus.

The article to be cleaned, such as a block M, is deposited on the rack 115 and the frame 101 is tilted inwardly through the opening 100. The frame 101 swings about a moving pivot provided by the arcuate edge 120 of the sections 103 rolling on the shelf 121 and the rollers 106 travelling along the guiding edge 107 until the shaft 112 strikes against the stops 119, in which position the block M is in position to be picked up by the conveyor 56 in a manner which will herein-after be described.

Referring now to Figs. 1 and 3, the conveyor 56 comprises driving heads 199, 200 mounted beyond the ends of the housing 50 and a plurality of spaced, and generally parallel, elongated cradles 201 extending between and carried by the driving heads 199 and 200.

Each cradle 201 (see Figs. 3 and 8) preferably comprises a shaft 190 carrying a plurality of longitudinally spaced forks 189, each including an arm 191 and arm 192 arranged substantially at right angles and secured to the shaft as by bolts 195 extending through an angle plate 196.

The driving heads 199, 200 are substantially identical in construction, hence only one of these will be described in detail. Referring to Fig. 1, the driving head 200 is rotatably mounted on a stub shaft 198 supported in frames 202 and 203 mounted on the support 49. Each frame 203

(see Figs. 4 and 6) may comprise an angle 204 secured as by rivets to a bracket 205 and a plurality of frame plates 206 connected by a bolt 207 extending therethrough and threaded into a frame block 208.

- 5 The driving head 200 (Fig. 6) comprises end plates 210 and 211 spaced by a cylindrical shell 212 and a ring 213 suitably secured to the end plates 210 and 211. The end plate 211 is secured to a flange 214 of a bearing sleeve 215 to which is secured a driving sprocket 216. A bolt 217 may extend through the plate 211, flange 214, and driving sprocket 216 for securing these members together. The bearing sleeve 215 is mounted 10 on the bearing member 208 and a bushing 219 is interposed therebetween and thrust washers 220 may be interposed between the ends of the bearing sleeve 215 and the bearing members 208 and 206, respectively.
- 15 20 The cylindrical shell 212 may be provided with one or more openings 221, closed by a removable cover plate 222, and the end plate 211 may have one or more openings closed by removable cover plates 224, thereby permitting access to the interior of the driving head 200 after it has been assembled.

25 30 The end plate 210 is provided with a central opening 230 in which is seated a main bearing 231 having a recess which carries a roller bearing 234. Packing 235, a sealing ring 236 and a sealing ring 237 may be provided for sealing the bearing 231. The bearing 231 may be secured to a plate 238 which, in turn, is secured to a cover plate 239 adapted to close an opening 240 in the end of the housing wall 241. Closure rings 242 and 243 may extend over the marginal portion of the plate 239 further to seal the opening 240.

35 40 Each cradle shaft 190 extends through an opening 246 in the end plate 210 and is journaled therein by a self-aligning bearing 247. The bearing 247 includes a pair of bearing plates 248 secured to the end plate 210 and defining a bearing seat 249 having bowed side walls. A bearing sleeve 250 having bulged side wall portions is seated in the bearing seat 249 and a bushing 252 is received in the sleeve. An end ring 254 and cover plate 255 are provided and a cover sleeve 256 is telescoped over the inner end of the bearing sleeve 250.

45 50 Slidable in the bushing 252 is a sleeve portion 257 of a driving member 258 which receives a reduced end 259 of the shaft 190. The reduced end 259 is connected to the driving member 258 by a key 260.

55 60 The cover plate 239 is formed with an opening 262 to accommodate the reduced shaft end 259 and the sleeve portion 257 of the driving member 258. The shaft 190 has a shoulder 263, and a collar 264 and a ring 265 are interposed in abutting relation between the shoulder 263 and the end of the sleeve portion 257. The ring 265 carries a sleeve 266 which telescopes about the cover sleeve 256 and slides within a flanged cover sleeve 267 carried by the plate 239 upstanding about the opening 262.

65 70 Each of the shafts 190 is supported in a manner similar to that just described and each opening 240 is sealed in a similar manner. Each shaft 190 is slidable longitudinally in its bearing sleeve 252 and carries with it the driving member 258, the collar 264 and ring 265 and the sealing sleeve 266. Thus, considerable longitudinal movement of the shaft 190 is possible and the sealing arrangement effectively prevents any abrasive from

passing through the opening 240 in the housing wall 241.

75 Integral with and extending laterally from the outer end of the driving member 258 are control crank arms 270 and 271. The crank arm 271 is provided at its end with a stud bolt 274 which is prevented from rotating by a key 275 and is secured by a nut 276. Rotatably carried by the bolt 274 and retained by a head 277 thereof is a guide roller 279. A similar guide roller 278 is carried in a similar manner by the arm 270.

80 85 Mounted in position to cooperate with the guide rollers 278 and 279 of the crank arms is a control cam 281 fixedly secured to the bearing block 208. The control cam 281 comprises a circular plate 15 282 and a cylindrical rim 283 secured together and serving as a supporting frame. The plate 282 is seated against a shoulder 284 in the bearing block 208 and is secured to a flange 285 by suitable means, such as bolts 287.

90 95 Referring now to Fig. 7, the plate 281 carries a plurality of flange members which cooperate with the rim member 283 in defining a plurality of cam track portions. Flange members 300 and 301 provide a track 302 and flange member 303 defines with flange member 301 a track 304. Flange member 305 defines with members 306 and 308 tracks 307 and 309 respectively. Flange members 310 and 311 define a cam track 312. Elongated flange members 313 and 314 define an elongated track 315. If desired, for convenience of manufacture the flange members 313 and 314 may be constituted by a plurality of members.

100 105 It will be seen that as the shafts 190 are rotated about their common axis and travel along the circular path indicated by the broken line *v*, the roller 278 of each crank 273 is guided by the tracks 302, 309 and 312 along a path indicated by the broken line *x*. During this movement the roller 279 is guided by cam tracks 304, 307 and 315 along a path indicated by the broken line *y*. It will be seen that each crank is at all times positively actuated by the various cam track portions in such a manner as to rock the shaft 190 through an angle of somewhat more than 90° in the course of one trip around the path *v*. Obviously this angle may be varied considerably by suitable formation of the cam tracks.

110 115 An inclined cam plate defining a riser cam 322 is secured to the frame plate 282 and has one end 323 terminating in the cam track 315 and the other end 324 terminating adjacent the end of the cam track 315. The plate 322 is formed with an upwardly inclined rise from the end 323 toward the end 324. Thus when each roller 279 is guided along the track 315 the head 277 rides onto the riser cam 322 and, as the head advances along the riser cam 322, the shaft 190 is urged longitudinally (to the right, as viewed in Figs. 3 and 4).

120 125 Referring now to Fig. 4, the driving head 199 at the charging end of the apparatus is constructed and supported in a manner similar to the driving head 200. Disposed in the driving head 199 at the charging end of the apparatus is a control cam 280 constructed and fixedly supported in a manner generally similar to the cam 281.

130 135 Referring now to Fig. 5, the cam 280 includes a plate 282 and rim 283 and a plurality of flange members secured to the plate 282. Flange members 400 and 401 define a track 402 and flange members 401 and 403 define a track 404. Flange members 405 and 406 define a track 407 and flange members 405 and 408 define a track 409. 75

Flange members 410 and 411 define a track 412. A flange member 413 including a plurality of members and flange member 414 also including a plurality of members, define an elongated track 5 415. A riser cam 422 is disposed with one end 423 projecting into the track 407 and the other end 424 projecting into the track 415, and is formed with an upwardly inclined rise from the leading end 423 to the departing end 424. This 10 cam operates to urge each shaft 190 to the left (as viewed in Figs. 3 and 6.)

It will be seen that the cam tracks of the cams 280 and 281 are complementary and that the cams act similarly upon the crank arms 270, 271 15 at the two ends of the shafts, thereby positively controlling the rocking of the shafts 190 as they are carried about their common axis. During the movement of each shaft through its uppermost position, it is simultaneously moved toward the 20 discharge end of the apparatus and during another portion of its travel along the path v , it is moved toward the charging end.

Referring now to Figs. 3 and 12, the apparatus 25 is provided with suitable discharge apparatus for receiving the blocks M from the conveyor and removing them from the housing after they have been treated. The portion 450 of each shaft 190 which projects into the discharge chamber 55 is formed cylindrically and a hollow cylindrical 30 drum 451 surrounds and is supported by the cylindrical portions 450. The drum 451 is formed with a flared or bell-mounted end 452 adapted to bear against a bracket 454 to position the drum 451 and to shield the adjacent mechanism.

35 The end of the drum 451 which is adjacent the cradle members may be suitably drawn out or otherwise formed to provide a plurality of tapered extensions 453 extending between each pair of adjacent shafts 190 to assist the block M in riding onto the drum 451 as the block is discharged 40 from the conveyor, and to connect the drum 451 to the shaft 190 for actuation thereby. Secured to the end wall of the housing 50 is a deflector 460 which prevents the block M from falling off 45 the drum 451 in the wrong direction.

Formed in the housing wall adjacent the discharge drum 451 is a discharge opening 465. A discharge chute 466 extends through the opening 465 and is suitably shaped to receive the block M 50 from the drum 451 and permit it to slide out through the discharge opening 465 and deposit it onto a suitable cushion 469 formed of suitable cushioning material, such as sponge rubber. The discharge opening 465 may be closed by one or 55 more flexible curtains 467 suspended from a bracket 468.

The conveyor 56 is driven from a suitable source of power such as an electric motor 470 (Figs. 1 and 2) which drives a speed reducer 60 472 which in turn actuates a chain 473 operatively connected to a drive shaft 474 journaled in bearings 475 and 476. The shaft 474 actuates a chain 477 at each end of the apparatus, and each chain 477 is trained over the corresponding 65 driving sprocket 216. When the motor 470 is energized it rotates the shaft 474 which in turn effects rotation simultaneously of the driving sprockets 216 at the ends of the apparatus and the corresponding driving heads 199 and 200.

70 Operation

The operation of the apparatus is as follows: A block M to be treated is deposited on the rack 115 and the loading frame 101 is pushed into the 75 loading chamber 53 until the shaft 112 strikes the

stops 119, in which position the block M is adapted to be engaged by certain of the forks 189 of one of the cradles 201. As the cradle 201 moves upwardly the forks 189 pass between the bars 116 of the rack 115 and lift the block M therefrom. The cradle 201 carrying the block continues to move upwardly to its uppermost position and then begins to descend on the other side of its path. 5

During the rotation of the cradles 201 about 10 their common axis they are rocked by the action of the control cams 280 and 281, as previously described, and hence the cradle 201 carrying the block M turns the block as it moves from left to right (as viewed in Fig. 8). Preferably, the 15 block M is turned about an axis extending generally in the direction of forward movement of the article and approximately passing through or near the block.

As the cradle 201 carrying the block M is rotated further in a clockwise direction, it is rocked to a position wherein the arms 192 are approximately horizontal and the arms 191 of the next succeeding cradle 201 are also approximately horizontal and approximately at the same level. 20 Upon further rotation of the conveyor, the arms 191 of the succeeding cradle 201 engage the block 25 M and lift it from the arms 192 of the first cradle 201. It will be noted that as each cradle 201 moves into a position to receive the block M, the arms 191 are displaced longitudinally from the arms 192 of the cradle which carries the block and thus can engage the block M prior to disengagement of the arms 192 of the preceding cradle. 30

The cradle 201 which receives the block M continues to rotate about the common axis of the cradles 201 and simultaneously to rock about the axis of its shaft 190. The cradle 201 turns the block M in a counter-clockwise direction (as 35 viewed in Figs. 8 to 11) and simultaneously carries the block in a clockwise direction. Thus, the net effect is a rotary movement of the block within a limited space and the movement approximates a rotation of the block about an axis passing through the block and parallel to the direction of forward movement.

During the portion of the movement of the cradle 201 wherein it carries the block M the riser cam 422 (Fig. 5) is effective to slide the shaft 50 190 longitudinally toward the discharge end (left-hand end, as viewed in Fig. 3) and thereby advances the block M. Thus the block M is engaged by certain forks of each cradle 201 in a position in advance of the position in which it was received by the preceding cradle. This results in a forward movement of the block M along the conveyor 56, simultaneously with the turning movement. 55

As the block M is advanced by the conveyor 56, 60 it enters the abrasive stream b and the particles impinge against the block from an angle determined by the shapes of the streams. In the present example, the abrasive at the entering end approaches from a substantially vertical direction. As the block is advanced through the stream b it is turned about and the various portions of the surface successively enter and pass through the stream laterally. If the block is relatively narrow and the stream is relatively 65 wide it will remain substantially in the stream during its entire travel. However, generally the stream will be somewhat narrower than the block and hence the various portions of the block pass into and out of the stream a plurality of times. 70 75

The block is further advanced in the stream and passes through portions of the stream having varying angles of impingement, the range of which may vary throughout a considerable angle, 5 which may considerably exceed 90°. Thus both front and rear wall surfaces as well as projections and cavities are struck by the particles. Preferably, the abrasive streams *b* and *c* are arranged oppositely so that the total angle approaches 180°.

When the block *M* is advanced to the end of the conveyor *56*, it is moved onto the discharge drum *451* and is deposited thereby onto the discharge chute *466* and slides out of the housing 15 and onto the cushion *469*. The deflector *460* prevents the block *M* from dropping off the drum on the opposite side from the discharge chute *466*.

From the foregoing, it will be seen that the present invention provides apparatus for conveniently and satisfactorily cleaning, polishing, 20 hardening, or otherwise modifying the surface characteristics of numerous types of castings, forgings, or other metallic objects. This apparatus is admirably adapted for the treatment of articles which are large and heavy or which have 25 projections or cavities and which cannot suitably be exposed to the abrasive treatment by tumbling. The apparatus is especially suited for cleaning or polishing cylinder blocks, bath tubs, 30 motor and generator frames, cast radiators, and various blocks, housings and other cast or forged articles or objects. Since the articles are gently handled and not dropped or jarred, there is no danger of breaking or injuring projections or 35 tensions or cracking fragile articles as, for example, brittle castings. The apparatus is also applicable to treating the inside surfaces of deep or irregularly shaped cavities since the articles are subjected to impingement by abrasive projected from varying angles.

Each article can be fully treated on all sides in the course of a single trip through the apparatus and the operation is a continuous one, thus maximum efficiency can be realized. The apparatus is adapted for automatic and production 45 line operation, suitable apparatus being provided for supplying articles to the present apparatus and conveying them therefrom. The apparatus is positive and reliable in operation and requires little attention on the part of an operator.

The apparatus is capable of being constructed in various sizes and can be designed to operate upon relatively large and heavy articles. The apparatus is easy to operate and can be readily 50 disassembled for the purpose of repairing or replacing parts. Substantially all of the wearing parts, with the exception of the cradles, are completely and effectively screened from the destructive action of the flying abrasive and hence are 55 not subject to rapid wearing. The arm portions of the cradles may be easily replaced when worn and, if desired, the cradle shafts may be made in sections to facilitate removal of the squared portions when they become worn out.

It is to be understood that where the expression "abrasive" or "abrasive particles" is used herein, it is not limited to a material consisting 60 of particles which are inherently abrasive. The material may consist of any one of a number of 65 materials of various characteristics as, for example, hard steel shot, cracked steel grits, quartz sand, or other material suitable for cleaning, polishing, hardening, or otherwise treating the 70 surfaces of the work piece. The particles may have 75 various sizes and characteristics depending upon

the result desired and may range from relatively large to relatively small particles and from relatively smooth particles, such as steel balls, to exceedingly sharp and abrasive particles, such as clean, sharp sand.

Various characteristics may be imparted to the surface of the work piece by employing various abrasive materials. For example, where it is desired to harden the surface of the article treated, a material consisting of hard, smooth and sizeable 10 particles, such as hard, round and smooth steel shot, may be employed. The smooth shot does not scratch or cut the surface of the work piece but exerts a peening or working action thereon and greatly increases the surface hardness.

Where it is desired to impart a stippled or roughened surface characteristic, relatively small, sharp particles, such as cracked steel grits or sharp, clean quartz sand, may be employed, and this material cuts pits or depressions in the surface of the work piece to provide the desired roughened surface.

While certain novel features of the invention have been disclosed and are pointed out in the annexed claims, it will be understood that various 25 omissions, substitutions and changes may be made by those skilled in the art without departing from the spirit of the invention.

What is claimed is:

1. Apparatus for abrasively treating metal articles including, means for projecting a stream of abrasive particles, and conveyor means for transporting an article to be treated through said stream, said conveyor means including a plurality of cradle members, means mounting said cradle 35 members for rotation about a common axis, means for actuating said cradle members to successively engage said article, means actuating one or more of said cradle members to advance said article in a generally horizontal direction through the stream, and means actuating one or more of said cradle elements to turn said article in the stream.

2. Apparatus for abrasively treating metal articles including, means for projecting a stream of abrasive particles, and conveyor means for transporting an article to be treated through said stream, said conveyor means including a pair of end frames, a plurality of cradle elements extending between and carried by said end frames, 45 means for rotating said end frames to move said cradle elements about a common axis, and cam means adjacent said end frames for individually 50 rocking certain of said cradle elements and for oscillating certain of said cradle elements longitudinally.

3. Apparatus for abrasively treating metal articles including, means for projecting a stream of treating particles, and conveyor means for transporting an article to be treated in a generally 60 horizontal direction through said stream and turning said article in the stream, said conveyor means including a plurality of cradle elements each having a plurality of laterally extending longitudinally spaced arms, end frames supporting 65 said cradle elements for rotation, and means for actuating said cradle elements individually whereby an arm of one cradle element passes by and between spaced arms of another cradle element to receive and remove said article from 70 the last-named cradle element during rotation thereof.

4. Apparatus for abrasively treating metal articles including, means for projecting a stream of abrasive particles, and conveyor means for 75

transporting an article to be treated through said stream, said conveyor means including a plurality of cradle elements having a plurality of spaced laterally extending arms, end frames supporting 5 said cradle elements for rotation about a common axis, means for actuating said cradle elements individually whereby certain arms of one of said cradle elements receive said article from arms of another cradle element at a predetermined point in the rotation of said cradle elements, and means for imparting a forward movement to said cradle elements while said article is supported thereon thereby to advance said article relative to said next succeeding cradle 10 element.

5. Apparatus for abrasively treating metal articles including, means for projecting a stream of abrasive particles, and conveyor means for transporting an article to be treated through said stream, said conveyor means including a plurality of spaced and generally parallel cradle elements each having laterally extending article-supporting arms, and means for moving said cradle elements successively into article-receiving position, the arms of each succeeding cradle element being longitudinally offset and adapted to engage said article prior to disengagement by the arms of the preceding cradle element.

30 the arms of the preceding crude element.

6. Apparatus for blast cleaning metallic articles including, means for projecting a stream of abrasive particles at blasting velocities, a conveyor for advancing the articles to be cleaned through said stream, and loading mechanism for depositing the article on said conveyor, said loading mechanism including a frame for carrying an article, means for moving said frame into article-discharging position, said conveyor including means associated therewith and operative to engage the article prior to disengagement of

35 said article from said loading frame and to remove the article from the frame.

40

7. Apparatus for blast cleaning metallic articles including, means for throwing a stream of particles at blasting velocities, a conveyor for 45 advancing the articles to be cleaned through said stream, a second conveyor for receiving and removing the articles from said first conveyor, said second conveyor having a movable, article-supporting surface, and means associated with said 50 first conveyor for engaging said article with said second conveyor prior to disengagement from said first conveyor whereby to deposit the article on said second conveyor gently and substantially without tumbling or shock.

55 8. Apparatus for treating metal articles including, abrasive projecting means, a conveyor for transporting the articles in treating contact with the abrasive projected by said means, said conveyor including an article-conveying member
60 and means for moving said member along a circuitous path, and means for loading articles onto said conveyor including a frame having an article-carrying rack formed with an opening to permit passage of said article-carrying member
65 therethrough, means mounting said frame for movement into position wherein said article-carrying member passes through said opening and lifts the article supported on said rack from said rack and onto said conveyor.

70 9. Apparatus for treating metal articles including, abrasive projecting means, a conveyor for transporting articles in treating contact with the abrasive projected by said means, said conveyor including a plurality of spaced cradles rotatable about a common axis and means for ac-

tuating said cradles to advance and turn the articles, and unloading means including a cylindrical member disposed adjacent the discharge end of said conveyor in a position to receive articles from said cradles, and means for rotating said cylindrical member to carry the articles away from said conveyor.

10. Apparatus for blast cleaning metallic articles including, means for projecting a stream of abrasive particles at blasting velocities, supporting elements arranged to successively engage and support the article to be cleaned, actuating means for advancing said supporting elements forwardly to carry the article supported thereon through said stream, actuating means for turning said supporting elements about an axis extending generally parallel to the direction of forward movement for turning the article about in the stream, said supporting elements being adapted to positively engage and maintain said article under positive control during the entire forward and turning movements. 15 20

11. Apparatus for blast cleaning metallic articles including, an element for supporting an article to be cleaned, means for turning said element and the article supported thereon a predetermined angular distance, means for advancing said element and the article supported thereon at substantially right angles to the turning movement thereof, a second supporting element operative to disengage the article from the supporting element first named, means for turning said second supporting element and the articles supported thereon a predetermined angular distance, means for advancing said second supporting element and the article supported thereon in a direction substantially at right angles to the direction of turning movement thereof, and an abrasive throwing wheel for projecting an abrasive stream of particles against the article successively supported on said first and second conveyor elements. 25 30 35 40

12. Apparatus for blast cleaning metallic articles including, means for projecting a stream of abrasive particles at blasting velocities, a plurality of spaced conveyor elements extending in the same general direction and arranged to successively engage and support the article to be cleaned, frame means mounting said conveyor elements for movement about a common axis, means mounting said conveyor elements for both angular movement and axial movement in said frame, means for rotating said frame about said common axis, actuating means for reciprocating said conveyor elements axially, and actuating means for turning said supporting elements about their individual axes as they are carried about their common axis, whereby said article is successively passed from one to another of said conveyor elements and is forwardly advanced thereby. 45 50 55 60

13. Abrading apparatus for cleaning metal articles including, in combination, centrifugal means operative to project a fan-shaped stream of abrasive particles, and a conveyor for transporting an article to be cleaned through said stream and turning it about in said stream, said conveyor including rotatably mounted end frames, a plurality of spaced article-supporting elements extending in the same general direction, each of said elements being rotatably mounted on said end frames, means for rotating said end frames and supporting elements about a common axis to carry articles supported on said supporting elements through said stream, means for turning 65 70

said supporting elements during rotation of said end frames thereby to turn the article about in said stream, and means for shifting said supporting elements axially.

5. 14. Abrading apparatus for cleaning metal articles including, means for projecting a stream of abrasive particles, and a conveyor for transporting an article to be cleaned through said stream and for turning it about in said stream, 10 said conveyor including a plurality of article-supporting elements extending in the same general direction, rotatably mounted end frames supporting said elements for movement about a common axis extending substantially in the direction 15 of said elements, means individually mounting said elements in said end frames for turning and axially reciprocal movement, means for moving said supporting elements and said end frames about said common axis, means for individually 20 rocking said supporting elements in said end frames, and means for individually reciprocating said supporting elements in an axial direction.

15. Apparatus for abrasively cleaning metal articles including, means for projecting a stream 25 of abrasive particles, and a conveyor for transporting an article to be cleaned through said stream, said conveyor including a plurality of article-supporting elements extending in the same general direction, rotatably mounted end frames 30 supporting said elements for movement about a common axis extending substantially in the direction of said elements, means mounting said elements in said end frames for individual turning movement, means for rotating said supporting 35 elements and said end frames about said common axis, and means for rocking said supporting elements as they are moved about said common axis, said means including a fixed cam member having guideways therein, and crank members 40 fixed to said supporting elements and engageable with said guideways for actuation thereby as said end frames are rotated.

16. Abrading apparatus for cleaning metal articles comprising a centrifugal machine for projecting a stream of abrasive particles, and a conveyor for transporting an article to be cleaned through said stream, said conveyor including a plurality of article-supporting elements extending in the same general direction, end frames mounting 45 said elements for movement about a common

axis extending substantially in a direction of said elements, means mounting said elements in said end frames for axial displacement therein, means for rotating said supporting elements and said end frames about said common axis, and means 5 for individually rotating and shifting said supporting elements axially as they are moved about said common axis, said means including a fixed cam member adjacent each end of said supporting elements and having risers thereon, and means on the ends of said supporting elements 10 engageable with the fixed cam members and movable along said risers.

17. Abrading apparatus for cleaning metal articles comprising means for establishing a 15 stream of abrasive particles, and a conveyor for transporting an article to be cleaned through said stream, said conveyor including a plurality of article-supporting elements extending in the same general direction, end frames mounting said 20 elements for movement about a common axis extending substantially in the direction of said elements, means mounting said elements in said end frames for turning movement and axial displacement, means for moving said supporting elements 25 and said end frames about said common axis, and means for imparting a turning and an axially reciprocating motion to said supporting elements as they are moved about said common axis, said last means including a fixed cam member having 30 a guideway thereon, a crank fixed to each of said supporting elements and having a portion movable along said guideway to turn said supporting elements, and a riser in said guideway for guiding said cranks to reciprocate said supporting 35 elements axially.

18. Abrading apparatus for cleaning metal articles comprising a centrifugal abrasive projector for throwing a stream of abrasive particles, and a conveyor for transporting an article to be 40 cleaned through said stream, said conveyor including rotatably mounted end frames, a plurality of article-supporting elements extending in the same general direction and rotatably mounted on said end frames, means for rotating 45 said end frames, and means including a normally stationary cam for imparting a turning and axially reciprocating motion to said supporting elements as said end frames are rotated.

DAVID C. TURNBULL.
